UNITED STATES PATENT OFFICE

LAFAYETTE EASTLICK AND WILLIAM W. EASTLICK, OF ORO FINO, CAL.

HYDRAULIC GRAVEL-ELEVATOR.

SPECIFICATION forming part of Letters Patent No. 351,969, dated November 2, 1886.

Application filed April 15, 1886. Serial No. 199,030. (No model.)

To all whom it may concern:

Be it known that we, LAFAYETTE EASTLICK and WILLIAM WALLACE EASTLICK, of Oro Fino, Siskiyou county, State of California, have 5 invented an Improvement in Hydraulic Gravel-Elevators; and we hereby declare the following to be a full, clear, and exact description of the same.

Our invention relates to the class of gravel-elevators used in hydraulic mining; and our invention consists in an open top-chute set at the proper angle, its upper end being arranged to discharge into the main flume, and in one or more branch water-pipes having nozzles entering the lower end of the chute, together with the arrangement of the feed-flume and the details of arrangement and construction of the elevator-chute, all of which we shall herein-after fully describe.

20 The elevator is intended for use in hydraulic mining operations where the beds are low, and where there is no dump, and the material has to be raised to secure the necessary dump. The necessity for this elevation requires but 25 the briefest explanation.

When the beds of auriferous gravel are low, or are so situated that they cannot be washed down directly into the main flume, it is obvious that some disposal must be made of the 30 material. It cannot be left in the workings, as it would cover them up, and therefore it must be carried away from them to the main flume, which, when higher than the beds, requires the elevation of the material. This object is usually effected by a closed-tight pipe, the upper end being in communication with the main chute and the lower end with the pit or hole in the bed into which the material is washed. A hydraulic nozzle connected with 35 a branch pipe containing water under pressure is let into the lower end of the elevator-pipe, and the force of the stream is such that it sucks in the material behind it, on the principle of an injector, and carries it up through the pipe.

40 We propose to do away with the tight-closed pipe and use an open-top chute, which is rendered effective as an elevator both by reason of its construction and the arrangement of the 45 hydraulic nozzle or nozzles in communication with its lower end, whereby the material which is fed to the chute is forced directly up by the

stream, not by suction, as is the case with the closed pipe, but by direct impact.

Referring to the accompanying drawings for 55 a more complete explanation of our invention, Figure 1 is a perspective view of our elevator and hydraulic nozzles. Fig. 2 is a view showing its use in the workings.

The elevator-chute A is composed of two 60 sides and a bottom, there being no top, so that the chute is open above. The interior walls both of the sides and bottom are lined with separate heavy blocks a, bolted to the chute in such a manner that each may be removed when 65 worn for the substitution of another. The chute is therefore practically indestructible—a very desirable result, as it is subjected to great frictional wear and tear. The whole chute is properly braced to increase its strength. B is 70 a nozzle let into the lower end of the chute through a cross-beam, b, which serves as a rest for the feed-flume, hereinafter described. The nozzle is on the end of the branch pipe C, communicating directly or indirectly with the ele- 75 vated water-source.

In some cases we may use a second or supplementary nozzle, D, connected with a second branch pipe, E. The nozzle D passes under the chute and opens into it at a point 80 higher up than the nozzle B. When we use this nozzle, we make the floor or bottom of the chute higher or thicker at its lower portion, so that an offset, a', is formed through which the nozzle enters.

85 In Fig. 2, F is the bed. G is the feed-flume into which the material is washed. This flume rests within the lower end of the elevator-chute A, and discharges its material therein immediately in front of nozzle B. H is the main 90 flume.

The elevator-chute is set at an inclination, say, of forty degrees, its lower end being in the bed F, and its upper end being arranged to discharge its contents either directly into the 95 flume H or against a cut in a bank, I, from which it flows back again into the flume. The force of the stream from nozzle B (which in our practice is a three-inch one connected with a fifteen-inch branch pipe, C, the water being under head of about two hundred and seventy-five feet) is so great that the material fed from flume G is forced directly by the impact of the stream up the elevator-chute into 100

the flume H or against the cut in bank I. This direct impact force enables us to use the open-top chute for an elevator instead of the closed pipe, the advantage being that the latter 5 is much more costly and wears out quickly with no chance to repair it as with our chute.

If the elevation be too great for the effective operation of the single nozzle B, we use the supplementary nozzle D in connection with it, 10 so that the material meets with a fresh impetus on its way up.

Having thus described our invention, what we claim as new, and desire to secure by Letters Patent, is—

15 1. The open-top hydraulic gravel-elevator chute A, having its lower end in the workings and supplied therefrom and its upper end in communication with the main flume above, and a hydraulic nozzle receiving water under 20 pressure and arranged at the base of the chute, so that the material is carried up the chute by the direct impact of the stream, substantially as herein described.

2. The open-top hydraulic gravel-elevator chute A, having its lower end in the workings 25 and supplied therefrom, and its upper end in communication with the main flume above, and hydraulic nozzles receiving water under pressure and arranged in the bottom of the 30 chute at different elevations, whereby the material is carried up the chute by successive direct impacts of the stream, substantially as herein described.

3. The open-top hydraulic gravel-elevator 35 chute A, having its lower end in the workings and supplied therefrom and its upper end in communication with the main flume above,

said chute having the separate blocks *a* as a lining for its walls, in combination with a hydraulic nozzle receiving water under pressure and arranged in the bottom of the chute, so that the material is carried up the chute by the direct impact of the stream, substantially as herein described. 40

4. The main flume H above, the feed-flume 45 G in the workings below, and the branch pipe C, receiving water under pressure, in combination with the open-top elevator-chute A, having its lower end in communication with the feed-flume G and its upper end in communication with the main flume H, and the nozzle B on the branch pipe C, and entering the lower end of chute, so that the material is carried up the chute by the force of the stream from the nozzle, substantially as herein described. 50

5. The main flume H above, the feed-flume G in the workings below, and the branch pipes C and E, receiving water under pressure, in combination with the open-top elevator-chute A, having its lower end in communication 60 with the feed-flume G and its upper end in communication with the main flume H, the nozzle B on the branch pipe C, entering the lower end of the chute, and the nozzle D on branch pipe E, entering the bottom of the chute at a 65 point higher up, substantially as herein described.

In witness whereof we have hereunto set our hands.

LAFAYETTE EASTLICK.
WILLIAM W. EASTLICK.
